(57) **CLAIM**

The ornamental design for a door sealing strip, as shown and described.

DESCRIPTION

FIG. 1 is a perspective view of my new design;
 FIG. 2 is another perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.

The appearance of any portion of the door sealing strip between the break lines shown in FIGS. 1–4 and 7–8 forms no part of the claimed design. The broken line break lines form no part of the claimed design.

1 Claim, 8 Drawing Sheets(56)
